(57) **CLAIM**

The ornamental design for a bottle, as shown and described.

DESCRIPTION

FIG. 1 is an isometric view of a base in accordance with the new design;

FIG. 2 is a side elevational view of FIG. 1, wherein all sides comprise a mirror image thereof;

FIG. 3 is a top plan view thereof; and,

FIG. 4 is bottom plan view thereof.

The broken lines shown in FIG. 4 represent portions of the bottle that form no part of the claimed design.
